UNITED STATES PATENT OFFICE

LOUIS S. THORNESS, OF RENTON, WASHINGTON

CABLEWAY

Application filed November 11, 1929. Serial No. 406,178.

My invention relates to overhead cableways and consists of an improvement in pendent supports sustained on upright standards intermediate the head and tail end standards supporting the carrying cable of the cableway. It is more particularly designed for application to cableways constructed for logging operations where the strain on the carrying cable is greatly varied by the different weights of the loads carried thereon, although it is equally useful employed in other cableways where the loads carried are more uniform. My invention is also designed to take a side strain as well as a vertical strain and thus pull logs from either side of the cableway before lifting them to be carried to landing place at the head end of the cableway.

The object of my invention is to provide an intermediate support and carriage whereby the load traveling on the cableway may be carried on and over the intermediate support with ease, though there may be some slack or droop in the carrying cable caused by the heavy strain thereon. By means of my improvement it is possible to greatly extend the length of a cableway without increasing the size of the carrying cable.

My invention comprises certain improvements of construction which will be herein-after described and then pointed out in the claims. In the accompanying drawings I have shown my invention in the forms of construction which are now most preferred by me and show the novelty of the operative parts.

Figure 1 is a partial side view of a cableway in miniature showing three intermediate standards with my improvements applied thereon; Fig. 2 is a front side view of my improved support with the carriage at the point of going onto and over the support; Fig. 3 is an end view of Fig. 2; Fig. 4 is an enlarged end view of the supporting sheave, and Fig. 5 is a side view of the same; Fig. 6 is a vertical cross section of the carrying cable and the supporting member on the line 6-6 of Fig. 7 with an end view of the carriage sheave; Fig. 7 is a front side view of that part of the support at the left of line 6-6;

Fig. 8 is an enlarged cross section of the cable supporting member at line 8-8 of Fig. 7 showing the thin metal strip designed to hold the carrying cable fixed in the saddle thereon; Fig. 9 is an enlarged side view of the traveling carriage on which the load is to be suspended; Fig. 10 is an end view of Fig. 9; Fig. 11 is a vertical section on the line 11-11 of Fig. 9; Fig. 12 is a horizontal cross section on the line 12-12 of Fig. 9 looking down; Fig. 13 is a horizontal cross section on the line 13-13 of Fig. 9 looking down; and Fig. 14 is a partial side view of a log and the means of suspension in a horizontal position from the carriage.

Like numerals of reference designate corresponding parts in each of the figures on the drawings.

In logging operations, particularly in the Northwestern States, temporary cableways are constructed to pull out the logs and carry them to a landing place for loading on railway cars or other conveyances. The standards for these cableways are provided by selecting trees of suitable strength and, after trimming and topping them, to attach the log carrying cableway supports thereto. By selecting trees that are in line, a cableway can be constructed any length desired for practical operation. Where trees cannot be selected in alinement, two trees can be selected near each other, each being on opposite sides of the cableway, and the carrying cable be supported between them.

In the logging industry there is a great difference in the weight of the logs to be carried. In carrying logs that weigh several tons, more or less difficulty is experienced in pulling the log carrying carriage over the intermediate supports. Where the supports are fixed and unyielding, great force is required, to pull the carriage onto and over the support, owing to the abrupt incline of the cable as the carriage approaches the support. The purpose of my invention is to provide an intermediate support that undulates or yields to the approaching carriage in such a way that it can be drawn over the support without undue strain on the pulling line.

Referring to the drawings Fig. 1 indicates a part of a logging cableway supported on some of the intermediate standards 1—1 and a log 2 being carried thereon. The head and tail end supports and the operative power machinery are not shown. They are so well known and understood that an exhibit of them is not required.

My newly improved support is shown suspended from a bracket 3 fixed on one of the intermediate standards 1. This or any other means for suspending the support may be of size and form to meet the strain thereon and to allow the load 2 to pass clear of the standard 1.

My invention comprises a steel or iron rail 4 of proper strength and of suitable length and so formed as to curve downward in the middle and at each end as shown in Fig. 2. The rail shown is made of an inverted T-bar with a coved saddle seat 5 brazed on its upper edge as more clearly shown in Figs. 6, 7 and 8. This rail may be made of any other stock material, such as angle iron or of rail-way rails with the cove saddle milled in the head of the rail. This curved rail is supported at the two high points 6—6 by one sided link-like stirrups 7—7, the lower ends being pivotally fixed into sockets brazed on the under side of the rail and the upper ends attached to the opposite ends of a short wire rope sling 9 which is carried on the sheave 10 suspended from the bracket 3. The carrying cable 11 rests in the cove saddle 5 and is held in place by a thin metal strap 12 bolted or brazed to the rail 4. This strap is sufficiently loose to allow the carrying cable 11 to slip to the right or left as may be caused by the strain thereon. These straps are at the summit of the rail curves where the cable 11 will be constantly resting in the cove saddle 5.

The load carrying carriage is more of a suggestion than a fixed form of construction. The two carrying sheaves 8—8 are to be spaced apart to correspond with the length of the rail 4. The sheaves indicated are designed to be mounted in boiler iron hangers 13 of sufficient strength and properly reinforced to resist the strain thereon. The hangers are curved outwardly as shown in Figs. 3 and 10 to pass clear of the rail 4. They are fixed together by horizontal bars 14 made of the same material. These bars 55 have extending ends spread apart to enclose loading sheaves 15. Over these sheaves are operated lifting and operating lines 16—16 operated from the power machinery previously mentioned but not shown. The lines 60 pass under and around the sheaves 17—17 in a loading bar 18, constructed similarly to bar 14, and have their stable ends fixed at the points 16a. The sheaves 17 are provided with a clevis 19 designed to receive or attach the lines 20—20 by which the log or load is

suspended from the carriage. The loading bar after the log is attached is lifted to the position shown where it is held by supporting hooks 21—21. These hooks are held out free by the loading man by the cords 22 till the bar is lifted to the proper height when they are let drop under to hold the bar in the position shown. The lines 16 are then free to operate the carriage. After reaching the landing place the bar 18 is again lifted clear of the hooks 21 which are again pulled aside and the bar and its load is lowered to the ground.

By using the mechanism herein shown and described, it is possible to pass the loaded carriage onto and over an intermediate cableway support with comparative ease. As the carriage approaches my improved support, it is obvious that the near end of the rail 4 will be drawn to incline downward to meet the incline of the loaded cableway while the tautness on the opposite end will hold the rail 4 from inclining too abruptly. The first sheave 8 will roll onto the rail support with ease and after passing the first summit of the support, will roll onto the downward incline of the center and thus impart an upward lift to the cable and cause the second sheave to pass onto supporting rail with less strain than if the rail 4 did not have the downward bend at its center. In passing off the support the action will be reversed with the load moving under perfect control.

It appears evident that the movement described will not be limited to the form of carriage shown, but will operate equally as effective with any other form of carriage in which the sheaves are spaced to comply with the length of the rail 4.

It is to be observed that the wire rope sling 9 suspended on the sheave 10 allows the rail 4 to undulate more effectively than if hung to a fixed pivot. It is to be further observed that the supporting bolt of the sheave 10 has a semi-cylindrical head which will let the sheave swing to either side when pulling logs from either side of the cableway to be loaded thereon.

I am aware that other forms of intermediate cableway supports have been devised and used, but none to my knowledge have a rope sling support and a curved rail support with two summits.

My invention is not limited to logging operations, but is applicable to any cableway where either varied or uniform loads are carried. It is to be noted that my invention can be largely made of stock materials and can be constructed at a minimum expense. It can be taken apart for taking down and setting up in new fields as is required in the logging industry.

Having described my invention, what I claim is:

1. In combination, a cableway, an intermediate

diate supporting standard for said cableway, and means for suspending said cableway from said standard, said means comprising a suspended sheave, a triangular sling on said sheave, and a cable carrying rail attached to said sling.

2. In combination, a cableway, an intermediate supporting standard for said cableway, means for suspending said cableway from said standard, said means comprising a suspended sheave, a triangular sling on said sheave, a cable carrying rail attached to said sling, and said carrying rail so formed as to curve downward at its middle and at each end.

3. In combination, a cableway, an intermediate supporting standard for said cableway, means for suspending said cableway from said standard, said means comprising a suspended sheave, a triangular sling on said sheave, a cable carrying rail attached to said sling, said carrying rail so formed as to curve downward at its middle and at each end, and a cove saddle in the top of said rail for the carrying cable of said cableway and means for holding said carrying cable within said saddle at the upper curves of said carrying rail.

4. In combination, a cableway, an intermediate supporting standard for said cableway, means for supporting said cableway from said standard, said means comprising a suspended sheave, a triangular sling on said sheave, a cable carrying rail attached to said sling, said carrying rail so formed as to curve downward at its middle and at each end, and said sling attached to said rail at the two upper curves of said rail to allow an undulating movement thereof.

5. In combination, a cableway, an intermediate supporting standard for said cableway, means for supporting said cableway from said standard, said means comprising a sheave, a triangular sling on said sheave, a cable carrying rail attached to said sling, said carrying rail so formed as to curve downward at its middle and at each end, and said cableway having load carrying sheaves mounted thereon, and said sheaves so spaced and fixed apart as to be most easily operated onto and over said suspended cableway support.

LOUIS S. THORNESS.
